UNITED STATES PATENT OFFICE.

ALDEN J. BUSH, OF COLUMBUS, OHIO.

DOOR CHECK AND CLOSER.

Application filed October 6, 1924. Serial No. 741,796.

To all whom it may concern:

Be it known that I, ALDEN J. BUSH, a citizen of the United States, residing at Columbus, in the county of Franklin and 5 State of Ohio, have invented certain new and useful Improvements in Door Checks and Closers, of which the following is a specification.

This invention relates to improvements 10 in door checks and closers, it relating particularly to a device in which the use of liquid and the difficulties incident thereto, are avoided, depending for its accuracy of operation upon pneumatic and friction brake 15 mechanism.

A main purpose of the invention is to 20 simplify the construction of a door check and closer in which accuracy of operation depends upon pneumatic and friction brake means, and to minimize the number of parts 25 and avoid the use of parts that will get out of order and cause trouble. To this end check valves and all forms of automatic valves are dispensed with, and, in lieu thereof, there is employed on each piston a single 30 non-automatic valve having its stopper adjustably arranged in the valve. This invention also permits of the use of a brake ring less stiff than those commonly used on a 35 device of this general character. The location of the adjustable valve is also important and in this device it has been so placed that it is readily accessible for manipulation, when a piston reaches the end of one of its 40 movements.

In this improved device there is employed 45 a cylinder, much shorter in length than the ones commonly used in no-liquid door checks and closers now on the market, and this 50 shortened cylinder is especially adapted for use with the non-automatic valve placed upon the piston.

In a general way, the piston movement 55 is somewhat the same as in the device illustrated in Letters Patent Reissue No. 14,674 to J. C. Schmidt, dated June 24, 1919, and reference is here made for a full description of the movements of the pneumatic means, whereby the vacuous condition present in one cylinder controls the first half of the closing movement of the door, and the compression of air in the other cylinder controls the other half of the movement, it being understood that the opening movement of the door is free from any interfer-

ence or resistance caused by the pneumatic and friction brake means.

With these and other objects in view, the invention consists in certain novel features of construction and combinations of parts, 60 as hereinafter set forth and pointed out in the claims.

In the accompanying drawings:

Fig. 1 is a view in front elevation of a door check and closer embodying the invention. 65

Fig. 2 is a top plan view of the same.

Fig. 3 is a longitudinal section.

Fig. 4 is a bottom plan view partly in section, showing the positions of the parts 70 when the door is open.

Fig. 5 is a view similar to Fig. 4 but showing the parts in a different position; lever arm 28 moves contra-clock wise in moving from position shown in Fig. 4 to that 75 of Fig. 5.

Figs. 6 and 7 are detail views of one of the pistons.

Figs. 8 and 9 are detail views of the brake 80 mechanism with the insert disk removed.

Fig. 10 is a section on line 10—10 of Fig. 9.

Like letters of reference apply to like parts throughout the different views.

1 represents the casing, provided with 85 cylinders, 2 and 3, which are disposed diametrically opposite one to the other, and communicate with the interior of said casing.

A friction element is located within the casing 1, so as to cooperate with the wall 90 thereof, and is connected with and controlled by the operation of pistons 4 and 5, in the respective cylinders 2 and 3, said friction element being connected with said pistons by means of piston rods 6 and 7. Each of the 95 pistons 4 and 5 is provided with a valve 9 (see Figs. 3 and 7).

The stoppers 10 for said valves are adjustably arranged, and when adjusted, remain 100 fixed in their adjusted position, thereby dispensing with valves having automatic operating parts, that are liable to cause trouble through failure always to operate properly. When the valve, in this improved arrangement, is adjusted to its proper position, the 105 same remains in a fixed position during all movements of the operating parts of the pneumatic means. An air inlet 12 in each valve permits air to pass into passages 11 and 13, and thence to the cylinders, and 110

stopper 10 of valve 9 is adjusted to allow the proper amount of air to pass into cylinders.

The friction element, above referred to, comprises two sections of a divided brake ring 14, which is provided with a friction element 15 to engage the inner wall of the casing 1 (see Fig. 9). These two sections of rings are slidingly connected one to the other, so that they are normally in inoperative position but are forced apart into operative position by the oscillation of block 16. One brake section has a projecting tongue-shaped part 17 and the other brake section has a grooved member 18 into which the tongue projects with the block 16 arranged between the inner wall of the groove and the end of the tongue. The two sections of the brake ring are mounted within a recess formed in the disk 19 which is rigid with the shaft 20 and when the block is oscillated there will be a camming action, such as will force the two brake sections apart, thereby causing frictional engagement of the brake 15 with the inner wall of the casing. The block 16 is secured to the arm 21 and as shown in Figs. 3 and 10 there projects from each side of the block 16 pintles 16' one of which fits within a bearing in the disk 19 and the other in a bearing formed in the insert disk 22 which is secured by screws *s* to disk 19. The arm 21 is secured to the block by one of the pintles and projects across the face of the disk 22, operating with stop mechanism hereinafter mentioned to prevent the setting of the brake during the opening movement of the door. The shaft 20 (Fig. 3) is journaled in bearings formed in said casing 1, and said shaft is rigidly connected with a sleeve 23 to which the spring 24 is secured as fully described in said reissue patent.

The connections to the arm 28 are substantially the same as in said reissue patent and an arm 29 is likewise secured to the door frame.

The cylinder 2 operates as a suction device to brake the door during the initial closing movement and cylinder 3 as a compression cylinder during the final closing movement, and the degree of suction and compression is regulated by valves 9. During the opening movement of the door the pistons cannot be retarded by reason of the arm 21 contacting against the stop device 30 projecting from the disk 22 (see Figs. 4 and 5). The free end of arm 21 is secured to the ends of piston rods 6 and 7 as in said former patent.

When the door opens, stop 30 which is secured to disk 22, travels in close proximity to arm 21 and will prevent any movement of said arm relative to the ring 14, but during the reverse movement of the parts, i. e., when the door is closing, the arm 21 may

move away from said stop and thereby the brake will be set as explained above. The opening 31 is for stop 30 to make this device suitable for either a right hand or left hand door.

Having thus described my invention, I claim:

1. In a structure of the character described, the combination of a movable closure with a braking device for same, the combination of an oscillating member controlled by said closure, with a connector mounted on said oscillating member capable of having a limited movement relatively to said member, pneumatic means for retarding the movement of said connector to cause it to have a relative movement to said oscillating member, a stop device for preventing the retardation of said connector during the movement of the movable device in one direction, while permitting a retardation during the movement of the movable device in the opposite direction.

2. In a door check, the combination of an oscillating member a movable closure device connected with said member, a connector mounted on said oscillating member, but capable of having a limited movement relative to said member, pneumatic means including a piston cylinder device having a single valved opening for said piston cylinder device, a stop device for preventing the retardation of the connector during the movement of the oscillating member in one direction, while permitting its retardation during the movement in the opposite direction.

3. In a door check, the combination of an oscillating member, a closure device connected with said oscillating member, a connector moving in unison with said oscillating member, but capable of having an additional movement relative to said member, pneumatic means connected with said connector, a valve having a non-automatic stopper in the piston of said pneumatic means and a stop device adjacent the connector, for preventing the retardation of the connector by the pneumatic means during the opening movement of the closure device.

4. In a device of the character described having a movable closure and braking device therefor, the combination of an oscillating member controlled by said closure, a connector mounted on said oscillating member capable of having a limited relative movement to said oscillating member, a stop device for holding said connector against movement during the opening movement of said closure, said stop device being capable of being moved to different positions to adapt it for use with both a right and left hand closure.

5. In a door check, the combination with

a spring actuated member, of a friction device connected therewith, operating means for said friction device and fluid means connected with said operating means for retarding the movement of the latter to effect the application of the friction device during the closing movement of the mechanism and a stop device for preventing the retarding

movement of said operating mechanism during the opening movements of the mechanism. 10

In testimony whereof, I have hereunto set my hand, this 24th day for September, 1924.

ALDEN J. BUSH.
